Patented Mar. 21, 1916.

UNITED STATES PATENT OFFICE.

EMIL BERTHOLD, OF CHICAGO, ILLINOIS, ASSIGNOR TO FRIDA BERTHOLD, OF CHICAGO, ILLINOIS.

COOKING UTENSIL.

1,176,127.

Specification of Letters Patent. Patented Mar. 21, 1916.

Application filed August 19, 1914. Serial No. 857,436.

To all whom it may concern:

Be it known that I, EMIL BERTHOLD, a citizen of the United States, residing at Chicago, in the county of Cook and State of Illinois, have invented certain new and useful Improvements in Cooking Utensils, of which the following is a specification.

This invention relates to new and useful improvements in cooking utensils generally, and doughnut cookers particularly, and is designed primarily to improve the device disclosed in Patent Number 1,047,608 granted December 17, 1912.

In the device of the patent above referred to it is necessary to open the basket manually as well as swing the same about its pivots in this manner. The present invention provides a means whereby the basket may be locked, and at the same time opened or swung about its pivots without manual contact with the basket.

With the above and other objects in view this invention consists in the construction, combination, and arrangement of parts, all as hereinafter more fully described, claimed and illustrated in the accompanying drawings.

Figure 1 is a plan view of the cooker. Fig. 2 is a side elevation showing in dotted lines the cover opened or raised. Fig. 3 is a similar view showing the basket swung about its pivots. Fig. 4 is a vertical section taken along line 4—4 of Fig. 1 to illustrate the lock between the sections of the basket and its operating means. Fig. 5 is a horizontal section taken along line 5—5 of Fig. 4 and illustrates the lock.

Reference being had more particularly to the drawing 10, and 11 designates two sections which make up the basket B of the cooker, said sections being hinged together at 12. These sections are stamped from sheet metal, the perforations therein being formed by the removal of portions of the metal. Beads 13, 14 are formed on the edges of the circumferential flanges 10' and 11' of the sections 10, and 11 respectively. The lower section 10 is provided with an aperture 16, in the flange 10' and below the bead 14 thereof, said aperture being diametrically disposed with respect to the hinge 12. It is with this aperture 16 that the latch carried by the upper section 11 co-operates

to lock the sections 10, and 11 together. This latch comprises a strip of spring metal 55 17 riveted or otherwise secured to the interior of the flange of the upper section 11, and rebent outwardly to form the hook 18 which enters the aperture 16 and engages under the bead 14 to secure the sections together. A second plate 19 is mounted between the latch 17 and flange 11' and has a right angular projection or arm 20 at its lower end which passes between the beads 13 and 14, the outer end of said arm or projection being curved as illustrated in Fig. 4. By creating a pressure on the outer curved end of the arm 20 the plate 19 will be forced against the latch 17, moving the same inwardly to release the hook 18 from engagement with the coöperating flange 10' and permit the sections to be opened. Therefore in order to move the arm 20 and plate 19 the upper section 11, adjacent to the latch 17, carries a bracket 21. The bracket is provided with an arm 22 which is curved over the bead 14 and terminates in the horizontal bearing 23, said bearing having a shaft 24 rotatably mounted therein in substantially the same horizontal plane 80 as the arm or projection 20. The outer end of this shaft 24 is flattened as at 24^a to furnish a mounting for the rod 25 which is mounted for oscillation therein. Keyed to the lower end of this rod 25 and resting 85 flush with the flattened portion 24^a of the shaft 24, is a cam 26 arranged to contact with the outer curved edge of the arm or projection 20 upon the proper oscillation of the rod 25. This cam 26 is provided with 90 a curved contact surface 26^a for coöperation with the arm 20 and it also has a stop 26^b at its opposite end. When the rod 25 is oscillated the cam 26 contacts with the arm or projection 20 and forces the latch 17 inwardly, thus releasing the upper section 11 and permitting it to be raised by a pull on the rod.

A plate 27 is pivoted on each side of the lower section 10 and is provided with the 100 extensions 28, which rest on the ground to retain the bail carried by said plates in a vertical position. This bail comprises the pair of wires 29, which are medially inter-twisted as at 30, with a ring 31, and have 105 their ends held parallel by the bars 32. The

ends of the wires 29 pass under the straps 33 formed from the plates 27 and are frictionally held thereby slidably. Mounted on the parallel ends of the wires 20 through the 5 medium of the straps 34 are the plates 35 which have the lugs 36 formed therefrom for engagement with the rim of a kettle to support the cooker. In this manner the cooker is supported in the kettle so that it 10 may swing about its pivots and at the same time it is possible to raise and lower it within the kettle by the adjustment of the plates 35.

The rod 25 terminates in a ring 37 and 15 passes through the ring 31 in the bail 30. This rod 25 is also provided with a medial hook 38, which, when the upper section 11 of the basket is released and raised by the 20 rod, will engage the ring and hold the section in its elevated position. If it is desired to swing the basket B about its pivots the rod 25 is pulled upwardly; and as the rod is secured to one side of the basket the same 25 will swing to the position in Fig. 3. By mounting the rod 25 on the shaft 24, this shaft being rotatably mounted, the said rod may swing with respect to the basket. When it is desired to reverse or turn the basket B over, the upper end of the rod 25, 30 is given a quick pull upward by the workman moving said rod from the position shown in full lines in Fig. 2 to the dotted line position of the rod in the same figure. This tilts the basket on its center pivots, 35 and said basket from its own momentum turns completely over reversing its position in the support, as shown in Fig. 3. When desired the upper or top section of the basket may be lifted or turned up from the 40 lower section as shown in dotted lines in Fig. 2. This is accomplished by pulling upward on the rod 25 after its lower end is unlocked or disengaged from the lower section and is for the purpose of exposing the 45 cooked articles so that they may be readily removed from the basket.

While the preferred form of the invention is shown and described, it will be understood that many changes may be made 50 in the details of construction without de-

parting from the spirit and scope hereof.

What is claimed is:

1. In a device of the class described, a support having side standards, and a horizontal top connecting member, a basket centrally pivoted between the lower portions of said standards, and having two hinged together sections, and a rod for turning said basket on its pivots secured at its lower end to one side of the basket; said rod being loosely and slidably mounted in the top connecting member of the support, and also being adapted to oscillate therein, to open the sections of the basket. 55

2. In a device of the class described, a support having side standards and a horizontal top connecting member, a basket centrally pivoted between the lower portion of said standards, and having two hinged together sections and a rod for turning said basket on its pivots and also opening said sections of the basket; said rod being loosely and slidably mounted in the top connecting member of the support and having its lower end detachably secured to the edge of the 75 basket intermediate its pivots. 60

3. In a device of the class described, a support having side standards, and a horizontal top connecting member, a basket centrally pivoted between the lower portions of the side standards and having two hinged together sections, a spring latch for detachably securing said sections together, means for releasing said spring latch, and a rod 80 loosely and slidably mounted in the top connecting member of the support and detachably secured to the edge of the basket intermediate its pivots, said rod being adapted to be oscillated to operate the spring latch 85 releasing means and to be pulled upward to 90 either open the sections or reverse the basket on its pivots.

In testimony whereof I have hereunto affixed my name in the presence of two witnesses.

EMIL BERTHOLD.
